UNITED STATES PATENT OFFICE.

FRANK LODER, OF LA FAYETTE, INDIANA.

HOBBY-HORSE AUTOMOBILE.

1,159,594.

Specification of Letters Patent.

Patented Nov. 9, 1915.

Application filed April 8, 1915. Serial No. 20,040.

To all whom it may concern:

Be it known that I, FRANK LODER, a citizen of the United States of America, residing at La Fayette, in the county of Tippecanoe and State of Indiana, have invented 5 a new and useful Hobby-Horse Automobile, of which the following is a specification, reference being had to the accompanying drawings illustrating same.

10 My invention relates to amusement devices, and more in particular to amusement devices such as hobby-horse amusement devices adapted to be operated in connection with automobiles or other vehicles.

15 The principal objects of my invention are, to provide a practical amusement device of the character above mentioned and to provide various improvements in such devices as will hereinafter be more fully set 20 forth.

Still other objects will be apparent from the following specification.

In the preferred embodiment of my invention I employ an automobile, or other 25 suitable vehicle, preferably equipped with a platform, and a plurality of hobby-horses or other passenger-carrying devices located above the platform and having mechanism attached thereto for operating same either 30 while the automobile or other vehicle is standing still or is traveling, or both. I also preferably provide a fence around the platform to prevent the passengers from falling off of the amusement device onto 35 the ground. I also preferably provide some sort of an automatic player somewhere on or in the amusement device and operably connect it with the passenger-carrying devices to operate therewith to supply music 40 to the passengers while the passenger-carrying devices are in operation.

In the accompanying drawings illustrating the preferred form of my invention, Figure 1 is a perspective view of one form 45 of amusement device of this invention, with the fence around the platform removed; Fig. 2 is a sectional elevation of the amusement device of the invention, taken longitudinally thereof, with portions shown in 50 elevation and portions shown in cross-section to show the interior mechanism of the vehicle; Fig. 3 is a cross-sectional view of a portion of the apparatus shown in Fig. 2, taken on line X—X thereof and showing 55 the co-operative relation of the two foot-operated friction clutches; and Fig. 4 is a

cross-sectional view of a portion of the apparatus shown in Fig. 2, taken on line Y—Y thereof with portions shown in elevation and showing one of the crank-shafts for 60 operating the hobby-horses or other passenger-carrying devices.

Like characters refer to like parts in the several figures.

Referring to the drawings, 1 is the automobile body, having wheels 2 2, a hood 3 within which is the engine for running the automobile, and otherwise constructed so as to adapt it for road service the same as other automobiles.

35 4 is a platform covering the body of the automobile back of the engine hood 3, and 5 5 are steps leading to the platform 4.

6 is a fence placed around the platform to keep the passengers from falling off of 75 the vehicle onto the ground. The fence 6 may be removable so as to be used or not as desired.

7 is a seat for the chauffeur.

8 is the steering wheel for the automobile.

9 is the main drive shaft for the automobile, which is preferably connected to the engine drive shaft by a friction clutch 10 which is operated by a foot lever 11. The 85 outer toothed portion 12 of the clutch 10 is connected rigidly to the engine drive shaft so as to always rotate therewith when the engine is running. The toothed portion 12 gears with another toothed portion 13 on 90 another friction clutch 14 which is operated by a foot lever 15. It will be readily seen that with this construction the toothed portion 13 of the clutch 14 always rotates when the toothed portion 12 rotates. Each 95 of the friction clutches 10 and 14 comprises an outer member 16 which carries the toothed portion 12 or 13, and an inner tapered member 17 adapted to fit within the outer member 16, the inner member 17 being operated along its shaft so as to clutch 100 with the clutch member 16 in a manner well understood, by means of a yoke member 18 straddling a collar member 19 which is operably connected with the member 17, the yoke member 18 being operated by its foot lever 11 or 15, preferably as shown in Fig. 2. The yoke members 18 18 and foot levers 11 and 15, are carried by a transversely-disposed rod the ends of which are 110 held to the frame 20 of the automobile by suitable brackets 21 21.

The shaft 22, extending longitudinally of the automobile, is connected with the clutch member 17 of clutch 14 so as to rotate therewith. The shaft 22 carries a pair of gear wheels 23 23 adapted to gear spirally with a pair of pinions 24 24, respectively, carried by respective crank shafts 25 25 transversely arranged with respect to the automobile and carried by the frame 20 20 of the automobile within suitable bearing members 26 26. By means of this construction a rotation of the shaft 22 causes a rotation of each of the shafts 25 25. Each of the transversely-disposed rods 27 27 carries a row of hobby-horses 28 28, or other passenger-carrying devices, preferably supported by members 29 29 as shown in Fig. 2. Each of the members 29 29 is caused to oscillate on its rod 27 by means of an operating member 30 pivotally attached to the member 29 as at 31 and also operably attached to the crank-shaft 25 as at 32. By this arrangement, when the crank-shaft 25 is rotated, the horses 28 28 connected therewith by the members 30 30 are caused to oscillate about the rod 27 much the same as a galloping motion of the horse. The cranks 32 32 on the crank-shafts 25 25 are preferably arranged so that they alternately extend in opposite directions, so that the horses 28 28 of each transverse row will have their heads up and down, alternately, at a particular instant. I also preferably arrange the mechanism so that each horse in a front row will have his head up while the horse directly back of him has his head down. This arrangement is thought to make a more pleasing operation of the horses as a whole.

Of course I wish it to be understood that various mechanisms may be employed in this invention for producing various movements of each individual horse or other passenger-carrying device, and also for producing various combinations of movements of the various horses or other passenger-carrying devices. The mechanism illustrated is simply one way of accomplishing the desired result. I also desire it to be understood that if desired I may operate the hobby-horses or other passenger-carrying devices from other sources of power beside the automobile engine, such as a storage battery, compressed air, etc.

I may, if desired, employ some sort of an automatic player 33 for providing music for the passengers, and belt same to a pulley 34 on the shaft 22 so that music will be provided whenever the horses 28 28 are operated. I may also equip the vehicle with numerous lights of various colors to attract attention at nights, if desired.

The device may be operated as follows:— When the clutch 10 is thrown in, the automobile is run from the engine. When the engine is running and clutch 14 is thrown

in, regardless of whether clutch 10 is thrown in or not, the hobby-horses are operated from the engine. The music player 33 is always operated with the hobby-horses. Thus, the automobile may be standing still and the hobby-horses may be operated, and then the automobile may be thrown into gear and run while the hobby-horses are still being operated. Also, while the automobile is running, the operation of the hobby-horses may be stopped, if desired, without stopping the automobile. Also, the automobile may be first started and then the hobby-horses later thrown into gear and operated. Also, both the automobile and the hobby-horses may be running, and then the automobile may be stopped without stopping the operation of the hobby-horses. These operations are possible on account of the two clutches 10 and 14 being operable independently of each other and both being operated from the engine.

I do not wish to limit this invention to the exact details herein set forth, as various modifications thereof may be made or utilized without departing from the scope of the appended claims.

What I claim as my invention is:

1. An amusement device of the character described, comprising an automobile having a platform thereon and steps leading thereto, a plurality of hobby-horses located above the platform, a fence around the hobby-horses near the edge of the platform, an engine for running the automobile, a foot-operated friction clutch driven by the engine for driving the automobile as desired, a second foot-operated friction clutch geared to the first said clutch whereby the second said clutch is also driven from the engine, 95 mechanism connecting the second said clutch with the hobby-horses whereby the latter are given a rocking movement, individually, when the second said clutch is thrown in and the engine is running, the said clutches 100 being operable independently of each other whereby the automobile and the hobby-horses may be operated independently of each other, a music player carried by the automobile and connected to be operated with the hobby-horses, and lights carried by the automobile for night illumination.

2. An amusement device of the character described, comprising an automobile having a platform thereon, a plurality of passenger-carrying devices located above the platform, a fence around the passenger-carrying devices, a source of power for running the automobile, a friction clutch driven from the source of power for driving the automobile 125 as desired, a second friction clutch geared to the first said clutch whereby the second said clutch is also driven from the said source of power, mechanism connecting the second said clutch with the passenger-carry- 130

ing devices whereby the latter are given a predetermined movement when the second said clutch is thrown in and is being operated from the said source of power, the said clutches being operable independently of each other whereby the automobile and the passenger-carrying devices may be operated independently of each other, and a music player carried by the automobile and 5 connected to be operated with the passenger-carrying devices.

3. An amusement device of the character described, comprising an automobile having a platform thereon, a plurality of passenger-carrying devices located above the platform, a source of power for running the automobile, and a pair of clutches both driven from the said source of power, one of the said clutches being for driving the 10 automobile from the said source of power as desired, the other said clutch having mechanism connecting it with the passenger-carrying devices whereby the latter may be operated in a predetermined manner from 15 the said source of power as desired, the said clutches being operable independently of each other whereby the said automobile and the passenger-carrying devices may be operated independently of each other.

20 4. An amusement device of the character described, comprising an automobile having a platform thereon, a plurality of hobby-horses located above the platform, an engine for running the automobile, a foot-operated 25 friction clutch driven by the engine, mechanism connecting the said clutch with the hobby-horses whereby the latter are given a rocking movement when the clutch is thrown in and the engine is running, and a music- 30 playing device carried by the automobile and connected to be operated with the hobby-horses.

40 5. An amusement device of the character described, comprising a one-car vehicle having a platform thereon, a plurality of hobby-horses located above the platform, an engine for running the vehicle, a foot-operated friction clutch driven by the engine, mechanism 45 connecting the said clutch with the hobby-horses whereby the latter are given a rocking movement when the clutch is thrown in and the engine is running, and a music-playing device carried by the vehicle and connected to be operated with the hobby-horses.

50 6. An amusement device of the character described, comprising an automobile having a platform thereon, a plurality of passenger-carrying devices located above the platform, an engine for running the automobile, a 55 clutch driven from the engine, mechanism connecting the clutch with the passenger-carrying devices whereby the latter are given a predetermined movement when the clutch is thrown in and the engine is running, and a music-playing device carried by the au-

tomobile and connected to be operated with the passenger-carrying devices.

7. An amusement device of the character described, comprising a one-car vehicle having a platform thereon, a plurality of passenger-carrying devices located above the platform, an engine for running the vehicle, a clutch driven from the engine, mechanism connecting the clutch with the passenger-carrying devices whereby the latter are given 70 a predetermined movement when the clutch is thrown in and the engine is running, and a music-playing device carried by the vehicle and connected to be operated with the passenger-carrying devices. 75

8. An amusement device of the character set forth, comprising an automobile having a platform thereon, a plurality of passenger-carrying devices located above the platform, an engine for running the automobile, mechanism driven by the engine and connected 80 with the passenger-carrying devices for operating them in a predetermined manner, and a music-playing device carried by the automobile and connected to be operated 85 with the passenger-carrying devices.

9. An amusement device of the character set forth, comprising a one-car vehicle having a platform thereon, a plurality of passenger-carrying devices located above the platform, an engine for running the vehicle, mechanism driven by the engine and connected with the passenger-carrying devices for operating them in a predetermined manner, and a music-playing device carried by 90 the vehicle and connected to be operated 95 with the passenger-carrying devices.

10. An amusement device of the character set forth, comprising an automobile having a platform thereon, a plurality of passenger-carrying devices located above the platform, a source of power carried by the automobile, mechanism driven from the source of power and connected with the passenger-carrying devices for operating them 100 in a predetermined manner, and a music-playing device carried by the automobile and connected to be operated with the passenger-carrying devices. 105

11. An amusement device of the character set forth, comprising a one-car vehicle having a platform thereon, a plurality of passenger-carrying devices located above the platform, a source of power carried by the vehicle, mechanism driven from the source of power and connected with the passenger-carrying devices for operating them in a predetermined manner, and a music-playing device carried by the vehicle and connected 110 to be operated with the passenger-carrying devices. 115

12. An amusement device of the character set forth, comprising a one-car vehicle having a platform thereon, a plurality of passenger-carrying devices located above the 120 125 130

platform, a source of power carried by the vehicle, a clutch driven from the source of power, mechanism connecting the clutch with the passenger-carrying devices whereby the latter are operated in a predetermined manner from the said source of power when the clutch is thrown in, and a music-playing device carried by the vehicle and connected to be operated with the passenger-carrying devices.

13. An amusement device of the character set forth, comprising a one-car vehicle, a plurality of passenger-carrying devices carried by the vehicle, a source of power carried by the vehicle, mechanism driven from the source of power and connected with the passenger-carrying devices for operating them in a predetermined manner, and a music-playing device carried by the vehicle and connected to be operated with the passenger-carrying devices.

14. An amusement device of the character set forth, comprising a one-car vehicle, a plurality of passenger-carrying devices carried by the vehicle, means for operating the passenger-carrying devices in a predetermined manner, and a music-playing device carried by the vehicle and connected to be operated with the passenger-carrying devices.

15. An amusement device of the character described, comprising a one-car vehicle having a platform thereon, a plurality of hobby-horses located above the platform, an engine for running the vehicle, mechanism driven by the engine and connected with the hobby-horses for operating them in a predetermined manner, the said mechanism having means for giving alternate hobby-horses different movements simultaneously, and a music-playing device carried by the vehicle and connected to be operated with the hobby-horses.

16. An amusement device of the character set forth, comprising a one-car vehicle having a platform thereon, a plurality of hobby-horses located above the platform, a source of power carried by the vehicle, mechanism driven from the source of power and connected with the hobby-horses for operating them in a predetermined manner, the said mechanism having means for giving adjacent hobby-horses different movements simultaneously, and a music-playing device carried by the vehicle and connected to be operated with the hobby-horses.

17. An amusement device of the character set forth, comprising a one-car vehicle, a plurality of passenger-carrying devices carried by the vehicle, a source of power carried by the vehicle, mechanism driven from the source of power and connected with the passenger-carrying devices for operating them in a predetermined manner, the said mechanism having means for giving alternate

passenger-carrying devices different movements simultaneously and a music-playing device carried by the vehicle and connected to be operated with the passenger-carrying devices.

18. An amusement device of the character set forth, comprising a one-car vehicle, a plurality of passenger-carrying devices carried by the vehicle, a source of power carried by the vehicle, mechanism driven from the source of power and connected with the passenger-carrying devices for operating them in a predetermined manner, the said mechanism having means for giving adjacent passenger-carrying devices different movements simultaneously, and a music-playing device carried by the vehicle and connected to be operated with the passenger-carrying devices.

19. An amusement device of the character set forth comprising an automobile, a plurality of passenger-carrying devices carried by the automobile, a source of power carried by the automobile, and a pair of foot-operated clutches both driven from the said source of power, one of the said clutches being connected for driving the automobile from the said source of power and the other having mechanism connecting it with the passenger-carrying devices whereby the latter may be operated in a predetermined manner from the said source of power, the said clutches being operable independently of each other whereby the automobile and the passenger-carrying devices may be operated independently of each other.

20. An amusement device of the character set forth comprising an automobile, a plurality of passenger-carrying devices carried by the automobile, a source of power carried by the automobile, mechanism for imparting a predetermined movement to the passenger-carrying devices, and means coöperating with the source of power and with the automobile and the said mechanism whereby the automobile and the passenger-carrying devices may be operated from the said source of power independently of each other.

21. An amusement device of the character set forth comprising a one-car vehicle, a plurality of passenger-carrying devices carried by the said vehicle, a source of power carried by the said vehicle, mechanism for imparting a predetermined movement to the passenger-carrying devices, and means coöperating with the source of power and with the said vehicle and the said mechanism whereby the said vehicle and the passenger-carrying devices may be operated from the said source of power independently of each other.

22. An amusement device of the character set forth comprising a one-car vehicle, a plurality of passenger-carrying devices carried by the said vehicle, a source of power carried by the said vehicle, mechanism for impart-

ing a predetermined movement to the passenger-carrying devices, and means coöperating with the source of power and with the said mechanism whereby the passenger-carrying devices may be operated from the said source of power independently of the operation of the said vehicle as desired.

23. An amusement device of the character set forth comprising a one-car vehicle, a plurality of passenger-carrying devices carried by the said vehicle, a source of power carried by the said vehicle for operating same and the said passenger-carrying devices, mechanism for imparting a predetermined move-

ment to the passenger-carrying devices and 15 associated with the said source of power for operation, and means coöperating with the said source of power and with the said vehicle for operating the latter, whereby the vehicle may be operated independently of 20 the operation of the passenger-carrying devices.

As inventor of the foregoing I hereunto subscribe my name, this 2 day of April, 1915.

FRANK LODER.
